UNITED STATES PATENT OFFICE.

WALTER HARRISON BIDDLE, OF EASTBOURNE, ENGLAND.

AUTOMATIC TRAIN-CONTROL APPARATUS.

1,303,631.

Specification of Letters Patent. Patented May 13, 1919.

Application filed February 11, 1916. Serial No. 77,736.

To all whom it may concern:

Be it known that I, WALTER HARRISON BIDDLE, a subject of the King of Great Britain, residing at Eastbourne, England, have 5 invented certain new and useful Improvements in Automatic Train-Control Apparatus, of which the following is a specification.

This invention relates to improvements in apparatus for controlling the operation of 10 trains either by actuating signals on trains or by stopping trains independently of the driver, or by employment of both of such train controlling means, the apparatus being of the type in which a movable track obstacle 15 or stop element which may or may not be moved simultaneously with an ordinary signal is adapted to actuate signaling or brake mechanism upon the train, so as to communicate to the driver the state of the road, 20 or of a corresponding signal, or to operate the brakes when the line ahead is not clear.

Many methods for applying this main idea have been proposed, but up to the present owing to difficulties of construction and 25 otherwise the idea has found no extended use upon railways. Apparatus has, for instance, been proposed comprising a track stop member, operable with the ordinary signals, a releasing or trip lever depending 30 from the train adapted to be actuated by said track stop member, and a gravity or spring operated device normally resting on this lever but adapted to be released by it to give a signal or stop the train and to remain 35 in the operative position until voluntarily returned to normal.

The present invention comprises the combination of these and other features and has for its object the simplification of the construction and the more certain operation of 40 such apparatus.

The invention will be fully described with reference to the accompanying drawings.

Figure 1 is a sectional side view showing 45 one arrangement of track stop member in the permanent way and the mechanism on the train adapted to be actuated thereby.

Fig. 1^a is a sectional side view showing the arrangement of the track stop member in 50 Fig. 1 combined with a second track stop member for actuating mechanism on the train to indicate when the line is clear.

Fig. 2 is a plan of a track stop member.

Fig. 3 is a diagrammatic view showing a locomotive provided with the apparatus. 55

Fig. 4 shows a modified form of engine mechanism.

Fig. 5 is a detail of same.

Fig. 6 shows a modified form of the apparatus. 60

Fig. 6^a is a sectional side view illustrating one of the spring catches for the trip lever shown in Fig. 6.

Fig. 7 shows a further modified form of 65 the apparatus.

Fig. 7^a is a sectional side view illustrating a spring catch arrangement included in Fig. 7.

Figs. 8 and 9 show two forms of apparatus adapted for indicating audibly when the line 70 is clear.

Fig. 10 shows the engine mechanism, illustrated in Fig. 4, combined with means for automatically returning the mechanism to normal position after it has been actuated 75 by the track stop member.

Fig. 11 is a plan view of a track stop member adapted to move horizontally.

At each place where the apparatus is to be employed, or at each ordinary signal in 80 connection with which the apparatus is to be used, there is arranged in the permanent way, as shown in Figs. 1, 2 and 3, either between the rails A or outside them one or two track stop members B adapted to be operated to engage a train contact, to be hereinafter described, when the line is blocked. 85 The track stop member B may be of any suitable construction but is preferably provided at its extremity with a double inclined face so arranged that when the contact member is raised to operative or danger position both faces have about the same inclination to the horizontal but in opposite directions. 90

As shown in the drawings, the track stop member B is arranged between the rails A and is mounted upon the shaft or rod d arranged across the line. This shaft or rod d may extend right across the line or only 100 so far as is necessary to operate the mechanism, and is mounted in suitable bearings adapted to hold it in position. At its outer extremity is mounted a weighted lever d² and a lever E, the latter being connected to 105 the operating or signal wire or chain e in

such a manner that when the line is clear or the signal is lowered to "line clear" the rod or shaft d is rotated so as to rock the track stop member B and when the line is 5 not clear or the signal is again raised to "danger" the shaft d is free to rotate back again under the influence of the weighted lever d^2 to again raise the track stop member B.

10 When one track stop member only is employed, this is preferably arranged centrally between the lines and the engine is then provided with one signaling or braking device such as hereinafter described, arranged centrally thereunder.

If one track stop member is employed arranged toward one side between the lines or outside the lines the engine or train is 20 preferably provided with two signaling or braking devices one at each side, in such a manner that the member B will be engaged whether the engine is traveling funnel first or tender first.

When the track stop member is not arranged centrally it is, however, preferable to 25 provide two members equidistant from the rails at either side and to provide the engine with one signaling or braking device adapted to engage one or other of the track stop 30 members according to the way the engine is traveling.

As described above, the weighted lever d^2 and the operating lever E are arranged outside the lines, but they may, if found desirable, be arranged between the lines, the operating or signal wire or chain being connected thereto by a flexible extension passing over suitable guide rollers in any convenient way.

40 Where employed with an ordinary signal the track stop member may be arranged directly at the corresponding signal or at any convenient distance in front of or beyond the signal.

45 Underneath the engine or the guard's van, or at both these places, or at any other part of the train is arranged a device adapted to be operated by the track stop member B above described to give a signal to the driver 50 or to stop or slow down the train.

Such device is shown in Fig. 1. To the under-frame F of the engine or other vehicle is attached a plate or frame G which carries the engine mechanism. Upon a pivot 55 h is mounted a lever H normally held in a more or less horizontal position but capable of swinging around on the pivot h under the influence of its own or an accessory weight, a spring or the like. Below

60 the lever H is mounted a pivoted trip lever K, one end of which h normally supports the weight or stress of the lever H and the other end of which is provided with a springy or elastic contact or detent member

65 J adapted to engage the track stop mem-

ber or detent B when this is raised. The contact member J consists of a brush-like attachment formed of bristles, wires, narrow strips of steel, or the like, of say 3 to 5 inches long. Such a brush contact is not 70 in itself new and no claim is made for it herein *per se*. The lower side of the lever H is formed with a wide V or like shaped recess or such a recess may be formed on the lower end h' of a lug or arm formed on the 75 lower side of the lever H, and the upper end h of the lever K is similarly formed of V or like shape to receive same, to prevent the lever K being too easily moved out of engagement with the lever H, for instance, by 80 the wind induced by the motion of the train.

When the member J of the lever K engages the track stop member B in its raised position it is moved to one side, and the upper end h of the lever K is forced to move 85 to one side and tends to move sufficiently with respect to the recess in the lower end of the lug h' so as to release the lever H which thereupon drops under the influence of gravity, its downward movement being 90 preferably limited or arrested by suitable means, such for instance as the valve operating mechanism hereinafter described.

The fall of the lever H when released may be employed alternatively to operate a sound 95 or visual signal or to put on the brakes or cut off steam or in any other way bring to the notice of the driver or the guard that a signal stands at "danger". Or the fall of the lever may produce any two or more of 100 these effects.

As shown in the drawing, the fall of the lever K is adapted to bring the train to a stop by putting on the brakes.

In the arrangement illustrated, the brakes 105 are shown operated by a compressed air brake and the fall of the lever H is adapted to open a valve N so as to permit air from the air reservoir to enter the train pipe O. It is, however, obvious that any exactly 110 similar arrangement may be employed in connection with the vacuum brake, the opening of the valve in this case permitting the entrance of atmospheric air to the vacuum pipe.

115 As shown, the valve N is arranged above the lever H and adapted to be opened by the upward movement of the valve, the valve spindle n resting on an extension h^2 of the lever H beyond the pivot h so that the fall 120 of the lever H raises the extension h^2 and lifts the valve spindle n and valve N to open it, the pressure in the air reservoir normally acting to maintain the end of valve spindle n pressed against the extension h^2 of the lever H. The valve may be operated by 125 means of a link motion connecting it positively to the lever. In Fig. 4, such an arrangement is shown, a link n' connecting the extremity h^2 of the lever H to the valve 130

spindle n ; the valve N in this case being constructed as a slide valve. Any other convenient type of valve may, however, be employed.

5 The distance within which the train may be brought to a stand-still is determined by the length of the opening provided in the valve N . By properly determining such distance the train may be stopped without any 10 shock.

If desired, a whistle o may be provided on the train pipe O adapted to be sounded by the inrush of air into the pipe to give a signal to the driver. Such an arrangement is 15 not in itself novel, it having been frequently proposed to employ the air entering or escaping from the brake pipe of a train to put on the brakes, to operate an audible or visual signal.

20 The whole device may be so arranged that it cannot be returned to normal position until the train has stopped, the driver being obliged to dismount from his engine to replace it, or means may be provided for 25 placing it from the foot-plate or other position, or means may be employed for automatically re-setting the apparatus.

For this purpose a chain or the like P (see Figs. 1 and 3) is attached to the end of the 30 lever H and leads up to the cab of the engine or other convenient position, where it is attached to a handle or other operating device by which the lever H can be raised. When it is so raised the lever K swings into normal 35 position and the lever H is dropped upon the upper end k thereof.

The chain P may if desired, in addition to being used for replacing the lever H , be employed for actuating a visual signal or a 40 whistle or for shutting off the steam or the like. Or it may operate a recording device p in connection with a tell-tale clock to indicate the number of times and the times of day that the device comes into use.

45 The lever K is preferably made in such a manner that the upper portion thereof is so much heavier than the lower portion that with the member J attached to the lever, the latter will normally remain vertical with 50 the member J lowermost but should the contact member J by any means be broken off, the upper end being heavier than the lower end and will not, when displaced return to the normal position upon the lever H being 55 raised, so that the brake cannot be taken off unless the bar is held up by other means.

To prevent or put a check upon any tampering with the apparatus by the driver while the train is moving, that is, to prevent 60 the driver holding the lever H up so that it does not fall when the lever K is caused to swing away by a track stop member B being raised, an auxiliary lever Q pivoted at q some distance behind the pivot h is employed. The free extremity q' of the lever

Q rests on the forward portion of the lever H and is arranged normally to coincide with the underside of a lug or the like n^2 arranged on the valve spindle n . As shown, the lug n^2 consists of a nut which may be screwed 70 on to the spindle and be also employed for adjusting the valve. It will be seen that if the lever H is raised by means of the chain P the lever Q will also be raised and lift the valve N so that air is admitted to the train 75 pipe O and will put on the brake.

In Fig. 6 of the drawings a somewhat simpler arrangement of engine mechanism is shown. In this form the lever K' and brush-like detent member J' are similar to 80 the parts K and J above described, but the upper end of the lever K' instead of supporting a drop member H is pivoted directly or otherwise positively connected to an arm or lever R adapted to operate a rotary or other slide valve or plug cock N' , 85 adapted to admit air to the train pipe. As shown, the lever K' is directly connected to the arm R by means of a pin k^2 working in a slot r in the lever R . Spring or other 90 catches S are provided to lock the lever K in the tilted position after it has been engaged by a contact member B so that the valve N' can not be at once closed by the lever K' swinging back to the vertical position and means such as a chain rod or the like P' capable of being operated by the driver may be provided for withdrawing the catches S to release the lever K' . Springs s or the like may also be provided to assist 100 the return of the arm R and lever K to normal position.

A somewhat similar arrangement is shown in Fig. 7. In this construction the lever K^2 and brush-like contact or detent member J^2 105 are similar to the corresponding parts hereinbefore described and the upper end k' of the lever K^2 is pivotally connected to one end of a link R' the other end of which is also pivotally connected to a lever H^2 110 mounted on a fixed pivot h^3 in such a manner that when the member J^2 is operated by the rail track stop member B the swinging movement of the lever K^2 draws down the lever H^2 . To the lever H^2 is also connected 115 the spindle n^3 of the valve N^2 for admission of air to the train pipe which is so arranged that the valve is opened on the drawing down of the lever H^2 . A catch device is provided to retain the lever in the lowered 120 position once it has been pulled down until it is released by the driver which may for instance be done by means of a chain or rod P^2 , which extends into the cab of the engine.

Such catch device may comprise, as shown in Fig. 7, a tongue spring S^2 fixed to the plate G and having a catch or lug S' which projects through a corresponding hole in the plate and is adapted to engage in a re- 130

cess h^4 in the trip plate or lever H^2 when the latter has been drawn down as explained above.

Where it is desired to return the apparatus 5 to normal position automatically, a dash pot arrangement may be employed. As shown the dash pot comprises a cylinder V in which is provided a piston W connected to the lever H^2 by means of a link w . The end 10 of the cylinder beyond the piston is provided with a valve X normally held closed by a spring but adapted to allow air to enter through it into the cylinder when the piston W is drawn down. A spring Y is 15 also provided adapted to return the piston W and with it the lever H^2 and the other parts to normal position. To adjust or regulate the time taken to return the parts the cylinder V is provided at its upper end with 20 an outlet pipe Z having a regulating cock z therein whereby the rate of flow of the air from the cylinder under the action of the piston W and spring Y may be regulated. When the dash pot is in use the spring S' 25 is preferably held out of engagement with the lever H^2 and on the other hand when it is desired that the apparatus should be operated by the driver, the regulating cock z is left wide open so as to offer but little resistance to the passage of air therethrough.

A dash pot device constructed and operating similarly to the dash pot device shown in Fig. 7 may be combined with the apparatus shown in Fig. 4 for the purpose of 35 automatically returning the rock lever therein to normal position after it has been actuated, the end k of the pivoted trip lever being for the purpose operatively connected to the lug h' by means of a link k^3 pivotally 40 attached by a pin k^4 to the lever and having a pin k^5 which projects into a slot h^5 provided on the lug h' . Such a combination is shown in Fig. 10 wherein V' is the dash pot cylinder, the piston W' thereof being 45 connected to the lever H by means of a link w' . A spring catch S^5 , similar in form and operation to the spring catch S' in Figs. 7 and 7^a, is provided for retaining the trip plate or lever H in the drawn-down position.

50 In one arrangement of the invention the contact member instead of being moved vertically may be adapted to move horizontally in which case the lever K would be swung sidewise instead of longitudinally of the train. Such an arrangement is illustrated 55 in Fig. 11, the track stop member B^2 being adapted to move horizontally about a vertical pivot d^5 from the danger position shown in full lines into the out-of-engagement position, indicated in broken lines,

60 when the signal is lowered to "line clear" on the signal wire or chain e' , connected to the arm E' of the stop B^2 being operated and to rotate back again under the influence of

the counterweight d^3 , connected to the arm E' by a chain e^2 , when the signal is again raised to danger.

Contact members B when operated by the signals in the manner described may be arranged at every signal on a line or only at 70 particular signals, say for instance, at every distant signal, to warn the driver to go carefully until he comes to the home signal.

In connection with any of the forms of apparatus above described, means may be 75 provided for indicating audibly to the driver that the line is clear or that a corresponding signal stands at "line clear". Two such arrangements are shown in Figs. 8 and 9, the former illustrating an arrangement in which the sounding device is in the 80 cab above the footplate and the latter an arrangement sounding below the footplate.

In either of these arrangements a second contact member is arranged between or near 85 the lines A operated from the same spindle d and in the same manner as the contact member B . Such an arrangement is illustrated in Fig. 1^a wherein the contact or stop member B , shown in Fig. 1, and a second 90 contact or stop member B' are both mounted on one and the same spindle d^4 and in such relative angular relation that the contact member B' will be raised when the contact member B is lowered and vice-versa. A 95 similar arrangement wherein a pair of track stops are adapted to move horizontally is indicated in Fig. 11, B^3 being the second track stop. The engine fitting comprises a lever 100 K^2 and contact member J^2 in general similar to the corresponding parts K and J above described. In the arrangement shown in Fig. 8, the lever K^2 operates through a suitable link and bell crank mechanism t a sliding rod T carrying strikers t' adapted to 105 engage a gong U as the rod T moves backward and forward under the action of any movement of the lever K^2 . Springs t^2 may be provided which are adapted to return the apparatus to normal position.

110 In the arrangement shown in Fig. 9, the lever K^3 carries a pivoted striker t^3 at its upper end adapted to engage a gong U' as the lever swings when it has been engaged by a contact member. Means may be provided in either arrangement for holding the sounding device out of operation. For instance, the lever K^2 or K^3 may be held to one side out of the operative position, or means may be provided for moving the gong 115 out of engagement with the striker or strikers.

120 It will be understood that the device in Fig. 8 or Fig. 9 can be used in combination with the engine mechanism shown in Fig. 10 arranged as in either Fig. 1^a or Fig. 11. In order not to cause confusion in the drawing, the devices in Figs. 8 and 9 are drawn

separately and not shown combined with the engine mechanism in Fig. 10.

Having thus described the said invention and the best means I know of carrying the 5 same into practical effect, I claim:

I claim as my invention:

1. In apparatus for controlling the operation of trains having a track stop adapted to be lowered or raised according to whether 10 the line is clear or is blocked, a pivoted tripping lever adapted to be carried on the train, resilient means on one end of said lever adapted to engage the stop without shock when the latter is in raised position, 15 the combination of a rock lever engaging the other end of said trip lever and adapted to be operated thereby, means operative by said rock lever for controlling the operation of the train, and means automatically 20 operative to lock the rock lever in the operated position after its engagement with the stop.

2. In apparatus for actuating signals on trains and for stopping trains having a 25 track stop adapted to be lowered or raised according to whether the line is clear or is blocked, a pivoted tripping lever adapted to be carried on the train, resilient means on one end of said lever adapted to engage 30 the stop without shock, when the latter is raised, the combination of a rock lever engaging the other end of said trip lever and adapted to be operated thereby, and means operative by said rock lever to simultaneously 35 brake the train and give a signal thereon.

3. In apparatus for controlling the operation of trains having a track stop adapted to be lowered or raised according to whether 40 the line is clear or is blocked, a pivoted tripping lever adapted to be carried on the train, resilient means on one end of said lever adapted to engage the stop without shock, when the latter is raised, the combination 45 of a rock lever engaging the other end of said trip lever and adapted to be operated thereby, a valve spindle and valve in the train brake pipe, means operatively connecting the rock lever and valve spindle, where- 50 by the said valve is controlled by said rock lever to slow down or stop the train.

4. In apparatus for controlling the operation of trains having a track stop adapted to be lowered or raised according to whether 55 the line is clear or is blocked, a pivoted tripping lever adapted to be carried on the train, resilient means on one end of said lever adapted to engage the stop without shock, when the latter is raised, the combination 60 of a rock lever engaging the other end of said trip lever and adapted to be operated thereby, means operative by said rock lever for controlling the operation of the train, and means operable on the train,

without descending therefrom, to return the 65 rock lever, after it has been operated, to normal position.

5. In apparatus for controlling the operation of trains having a track stop adapted to be lowered or raised according to whether 70 the line is clear or is blocked, a pivoted tripping lever adapted to be carried on the train, resilient means on one end of said lever adapted to engage the stop without shock, when the latter is raised, the combination of a rock lever engaging the other 75 end of said trip lever and adapted to be operated thereby, means operative by said rock lever for controlling the operation of the train, and automatic means for returning said rock lever, after it has been operated, to normal position.

6. In apparatus for controlling the operation of trains having a track stop adapted to be lowered or raised according to whether 80 the line is clear or is blocked, a pivoted tripping lever adapted to be carried on the train, resilient means on one end of said lever adapted to engage the stop without shock, when the latter is raised, the combination of a rock lever engaging the other 85 end of said trip lever and adapted to be operated thereby, means operative by said rock lever for controlling the operation of the train, manual means operable on the 90 train, without descending therefrom, to restore the apparatus, after it has been operated, to normal position, and checking means responsive to an unauthorized use of 95 said restoring means.

7. In apparatus for controlling the operation of trains having a track stop adapted to be lowered or raised, according to whether the line is clear or is blocked, a pivoted tripping lever adapted to be carried on the 105 train, the combination of resilient means on said lever to engage the stop without shock, when the latter is raised, a rock lever engaging the other end of said trip lever and adapted to be operated thereby, means oper- 110 ative by said rock lever for controlling the operation of the train, and means for giving an audible signal on the train at the end of a block or section when the line is clear ahead of the train.

8. In apparatus for controlling the operation of trains having a movable track stop adapted to be arranged in the permanent way, a pivoted tripping lever adapted to be carried on the train and having resilient 120 contact means for engaging the stop, the combination of a gravity-operated lever normally held up by said tripping lever, a valve in the train brake pipe operative by the release of said gravity lever, and means for 125 returning the last said lever and valve to normal positions.

9. In apparatus for controlling the opera-

- tion of trains having a movable track stop adapted to be arranged in the permanent way, a pivoted tripping lever adapted to be carried on the train and having resilient contact means for engaging the stop, the combination of a gravity-operated lever normally held up by said tripping lever, a valve in the train brake pipe operative by the release of said gravity lever, means for resetting the last said lever after operation, and a pivoted check lever adapted at its free extremity to rest on the gravity lever and, on the unauthorized raising of said gravity lever, to operate the said valve.
- 10 10. In apparatus for controlling the operation of trains having a movable track stop adapted to be arranged in the permanent way, a pivoted tripping lever adapted to be carried on the train and having resilient contact means for engaging the stop, the combination of a gravity-operated lever normally held up by said tripping lever, a valve in the train brake pipe operative by the release of said gravity lever, and a dashpot operative automatically to return the apparatus to normal position a certain time after it has been operated.
- 15 20 25

11. In apparatus for controlling the operation of trains having a track stop adapted to be lowered or raised according to whether the line is clear or is blocked, and a pivoted tripping lever adapted to be carried on the train having resilient means on one end for engaging the the stop without shock, when the latter is raised, the combination of a rock lever engaging the other end of said trip lever and adapted to be operated thereby, means operative by said rock lever for controlling the operation of the train, a second movable track stop adapted to be located in the permanent way, a tripping lever adapted to be carried on the train and adapted to be operated by the said second stop when the line is clear, and a signal on the train adapted to be operated by said tripping lever.

In testimony whereof I have signed my name to this specification in the presence of two subscribing witnesses.

WALTER HARRISON BIDDLE.
